Primary Examiner — Jeffrey D Asch*Assistant Examiner* — Caitlin A Laverty(74) *Attorney, Agent, or Firm* — Skaar Ulbrich Macari, P.A.(57) **CLAIM**

The ornamental design for a radio holster, as shown and described.

DESCRIPTION

FIG. 1 is a front perspective view of a radio holster showing our new design holding a radio shown in broken lines;

FIG. 2 is a front perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines shown within shaded areas of the radio holster represent stitching and form part of the claimed design.
